CLAIM

The ornamental design for a re-closable lid assembly with imbedded liquid diverting structure, as shown and described.

DESCRIPTION

FIG. 1 is an anterior top perspective view of a re-closable lid assembly with imbedded liquid diverting structure.

FIG. 2 is a top plan view of the re-closable lid assembly with imbedded liquid diverting structure, thereof.

FIG. 3 is a top plan view of the re-closable lid assembly with imbedded liquid diverting structure of FIG. 1 rotated to an open position.

FIG. 4 is an anterior top perspective view of the re-closable lid assembly with imbedded liquid diverting structure, thereof.

FIG. 5 is a top plan view of the re-closable lid assembly with imbedded liquid diverting structure of FIG. 1 rotated to a closed position.

FIG. 6 is an anterior top perspective view of the re-closable lid assembly with imbedded liquid diverting structure of FIG. 1, thereof.

FIG. 7 is a bottom plan view of the re-closable lid assembly with imbedded liquid diverting structure feature portion removed.

FIG. 8 is an anterior top perspective view of the re-closable lid assembly with imbedded liquid diverting structure of FIG. 1 showing the liquid diverting structure feature portion removed therefrom.

FIG. 9 is a posterior bottom perspective view of the liquid diverting structure feature portion of the re-closable lid assembly with imbedded liquid diverting structure of FIG. 1, shown removed from the re-closable lid.

FIG. 10 is a posterior top perspective view thereof.

FIG. 11 is a posterior side elevational view thereof.

FIG. 12 is an anterior side elevational view thereof.

FIG. 13 is a first lateral elevational view of the re-closable lid assembly with imbedded liquid diverting structure of FIG. 1.

FIG. 14 is a posterior elevational view, thereof.

FIG. 15 is a second lateral elevational view, thereof.

FIG. 16 is an anterior elevational view, thereof; and,

(Continued)

FIG. 17 is an anterior top perspective view of the re-closable lid assembly with imbedded liquid diverting structure of FIG. 1 shown in a position of use attached to a cup drawn in broken lines.

The broken lines in FIGS. 1-10, 14 and 17 illustrating text and arrows depict portions of the re-closable lid assembly with imbedded liquid diverting structure that form no part of the claimed design. The broken lines in FIG. 17 illustrating a cup depict environmental subject matter and form no part of the claimed design.
